UNITED STATES PATENT OFFICE.

THOMAS J. JONES, OF PULASKI CITY, VIRGINIA.

APPARATUS FOR REFINING ZINC SPELTER.

SPECIFICATION forming part of Letters Patent No. 540,671, dated June 11, 1895.

Application filed February 26, 1895. Serial No. 539,757. (No model.)

To all whom it may concern:

Be it known that I, THOMAS J. JONES, a citizen of the United States, residing at Pulaski City, in the county of Pulaski and State of 5 Virginia, have invented a new and useful Apparatus for Refining Zinc Spelter, of which the following is a specification.

This invention relates to apparatus for refining zinc spelter; and it has for its objects to 10 effect certain improvements in apparatus of this character and to provide positive and efficient means for thoroughly refining ordinary commercial zinc spelter to free the same from lead and other impurities.

15 To this end the main and primary object of the present invention is to construct an apparatus that will provide for the thorough elimination of lead and other impurities from the zinc spelter of commerce, thereby converting the same into a high grade, chemically pure, zinc spelter having a high market value.

With these and other objects in view, which will readily appear as the nature of the invention is better understood, the same consists 20 in the novel construction, combination, and arrangement of parts hereinafter more fully described, illustrated, and claimed.

In the drawings, Figure 1 is a vertical sectional view of a refining apparatus embodying the improvements contemplated by the present invention. Fig. 2 is a similar view showing a slightly-modified form of the apparatus. Fig. 3 is an enlarged detail sectional view of one of the hollow conical condensers 35 of the apparatus.

Referring to the accompanying drawings, 1 designates a furnace of an ordinary construction having the usual retort chamber 2, and the lower fire box 3, communicating with the 40 retort chamber 2, and the said furnace 1, which is arranged in an upright position, is provided with the front and back walls 4 and 5, respectively. The front and back walls 4 and 5 of the furnace 1, are provided with a vertical series of supporting shelves 6, and the supporting shelves of the front wall are located in a different horizontal plane from the shelves of the back wall, thereby providing means for supporting at a proper inclination 45 within the furnace the retorts 7.

The retorts 7, are grouped within the retort chamber 2, of the furnace in a regular series

in the ordinary manner, but in the present invention, the shelves 6, of the front and back walls provide for supporting the retorts at an 55 inclination with the front ends thereof disposed in higher planes than their rear ends, which rest on the shelves of the back wall. The said retorts 7, are made cylindrical in cross section, and in the present invention are 60 preferably provided with the closed rear ends 8, and the open front ends 9, in which open ends 9, are suitably fitted the wide flared ends of the hollow conical condensers 10, that are projected at the front side of the furnace. 65

The hollow conical condensers 10, are made of the usual material, but in the present invention are provided at their wide flared ends, within the open ends of the retorts 7, with the integral dam-diaphragms 11. The integral 70 dam-diaphragms 11, of the hollow conical condensers 10, extend partially across the inner wide ends of the condensers 10, to leave over their upper edges the vapor passages 12, which allow the zinc vapor to pass from within the 75 retorts into the condensers, while at the same time the dam-diaphragms prevent the back-flow of molten zinc spelter into the retorts 7.

In the operation of the apparatus in connection with the form illustrated in Fig. 1, the 80 zinc to be refined, is previously cast into billets or sticks that are introduced through the outer small ends of the condensers 10, and over the dam-diaphragms 11, into the retorts 7. The temperature within the furnace is 85 then raised to and maintained at a degree ranging between the boiling points of lead and zinc, that is, above the boiling point of zinc and below the boiling point of lead. By maintaining this comparatively low temperature 90 within the furnace, the zinc will be caused to volatilize, and the zinc vapor will pass over the dam-diaphragms 11, through the vapor passages 12, into the condensers 10, where the vapor strikes the cooler surfaces of the condensers, and is completely condensed. The 95 lead and other impurities, which are not volatilized by the heat of the furnace, remain in the retorts and, following the inclination thereof, run to the back end of the retorts out 100 of the way, the dam-diaphragms 11, practically cutting off the condensed zinc vapor from the retorts, thereby insuring the collection of pure zinc spelter within the condens-

ers, from which the same can be collected from time to time in any suitable manner. The retorts are cleaned from time to time of the accumulations of lead and other impurities by removing the same entirely from within the furnace.

A slight modification of the apparatus is observed in Fig. 2 of the drawings, in which the rear closed ends 8, of the retorts are provided with charging-slots 13, which are luted or otherwise closed air tight during the operation of the apparatus. In this form of the apparatus, the back wall of the furnace is constructed similarly to the front wall in order to leave the rear ends of the retorts exposed, so that the slabs of zinc can be introduced directly through the slots into the retorts without the necessity of charging the retorts through the condensers that are fitted in the open ends thereof. By reason of providing the slots 13, remelting of the zinc spelter into billets is rendered unnecessary, as is the case where the retorts are charged through the condensers, and furthermore the exposure, of the rear ends of the retorts having the slots, gives the added advantage of keeping the rear ends of the retorts comparatively cool, thereby materially assisting in securing the separation of the impurities of the spelter which follow the inclination of the retorts to the coolest point.

In the modified arrangement described, the process is precisely the same as described in connection with the arrangement of parts illustrated in Fig. 1.

Changes in the form, proportion and the minor details of construction may be resorted to without departing from the principle or sacrificing any of the advantages of this invention.

Having thus described the invention, what is claimed, and desired to be secured by Letters Patent, is—

In an apparatus for refining zinc spelter, the combination with the furnace; of retorts arranged at an inclination within the furnace and provided with normally closed rear ends and open front ends, the open frontends of the retorts being disposed in higher planes than their rear ends to provide for directing the non-volatilized matter away from said open front ends, and hollow conical condensers registering at their wide flared ends within the open front ends of the retorts to form closures for such ends, said condensers being provided at their wide ends within the retorts with integral vertically-disposed dam-diaphragms extending upward partially across the inner wide ends of the condensers to form vapor passages over their upper edges and prevent the back flow of the refined spelter into the retorts, substantially as set forth.

In testimony that I claim the foregoing as my own I have hereto affixed my signature in the presence of two witnesses.

THOMAS J. JONES.
